UNITED STATES PATENT OFFICE.

CHARLES C. GEBHARDT, OF RICHMOND, VIRGINIA.

EXPANSION-BOLT.

1,052,237.

Specification of Letters Patent.

Patented Feb. 4, 1913.

Application filed March 30, 1912. Serial No. 687,405.

To all whom it may concern:

Be it known that I, CHARLES C. GEBHARDT, a citizen of the United States, residing at Richmond, in the county of Henrico and State of Virginia, have invented new and useful Improvements in Expansion-Bolts, of which the following is a specification.

This invention relates to expansion bolts, 10 the object in view being to provide a bolt of the character specified which is capable of a large amount of expansion, so as to adapt it to fit tightly within holes of widely varying diameter.

15 A further object of the invention is to provide in connection with an outer shell and a bolt coöperating therewith, means whereby the bolt is securely held and prevented from escaping; after the shell has 20 been expanded by means of the bolt.

With the above and other objects in view, the invention consists of the construction, combination and arrangement of parts, as will be hereinafter more fully described, 25 illustrated in the accompanying drawings, and pointed out in the claim hereunto appended.

In the drawings: Figure 1 is a plan view of the bolt and casing complete. Fig. 2 is 30 a plan view of the bolt removed from the casing. Fig. 3 is a longitudinal section through the bolt. Fig. 4 is a cross section through the same.

The expansion bolt of this invention 35 embodies essentially an outer casing or shell 1, which is divided diametrically and longitudinally into two equal sections.

While the casing, as a whole, is cylindrical in its outer contour, it will be observed 40 that the casing is interiorly tapered from end to end, the larger end portion of the casing being adapted to primarily receive the head of the bolt 2.

In carrying out the present invention, the opposing sections of the shell or casing are 45 internally formed with annular grooves and shoulders, forming steps 3 of progressively decreasing diameter from the larger toward the smaller end of the casing.

The head 4 of the bolt is made tapering 50 on the inner side thereof, as shown at 5, so that as the bolt proper is drawn through the sectional casing or shell by means of the usual nut 6, the inclined face of the head of the bolt will ride over and past the steps 55 upon the interior of the shell, permitting the angular margin 7 of the bolt head to snap into the grooves upon the interior of the shell. This avoids any possibility of the bolt slipping backward and escaping 60 from the expansion shell of the device, in the event of the nut working loose on the bolt. Furthermore, by reason of the arrangement illustrated and described, the shell may be considerably expanded in size, 65 thereby adapting the expansion bolt, as a whole, to be firmly engaged with holes of greatly varying sizes.

What is claimed is:

An expansion bolt, comprising a cylindrical shell of uniform outside diameter having a longitudinal bore which tapers uniformly from end to end and also having annular grooves formed in the tapering wall of said bore, said shell being diametrically 75 divided into separable sections, and a bolt extending lengthwise of said bore and having a beveled head adapted to seat itself in said grooves as it is drawn through the shell.

In testimony whereof I affix my signature 80 in presence of two witnesses.

CHARLES C. GEBHARDT.
